UNITED STATES PATENT OFFICE.

LOUIS FERGUSON, OF NEW YORK, N. Y., ASSIGNOR TO FERGUSON BROTHERS MANUFACTURING COMPANY, OF HOBOKEN, NEW JERSEY.

FOLDING TABLE

Application filed August 27, 1921. Serial No. 426,112.

To all whom it may concern:

Be it known that I, LOUIS FERGUSON, a citizen of the United States, and resident of the borough of Manhattan, in the city and State of New York, have invented a new and useful Improvement in Folding Tables, of which the following is a specification.

The object of my invention is to provide a novel brace construction for each leg of a folding table whereby a device is provided which serves both as a stop for preventing the unfolding of the leg beyond its normal unfolded position, and also as a convenient handle for releasing the brace when it is desired to fold the leg.

My improvement is shown as applied to that type of folding table in which the swinging leg brace is pivoted to the table and is slidably connected to the leg through

20 a pivoted keeper.

A practical embodiment of my invention is represented in the accompanying drawings, in which,

Fig. 1 represents an inverted plan view of 25 the table with the legs folded.

Fig. 2 represents a detail side elevation of the table with the legs in their unfolded position.

Fig. 3 represents a detail side view on an 30 enlarged scale, showing the parts at the connection between the brace and leg.

Fig. 4 represents a similar view with the keeper and lock pin shown in section.

Fig. 5 represents a detail view partly in 35 side elevation and partly in section, showing the parts at the pivotal connections of the swinging brace and leg to the table.

Fig. 6 represents a detail inverted plan view of the table with one of the legs in its 40 unfolded position.

Fig. 7 represents a detail view taken at right angles to Fig. 3.

The encircling frame of the table is denoted by 1 and the folding legs by 2. In the 45 present instance each of these folding legs is shown as provided with a laterally extended hub 3 pivotally secured between a block 4 and the table frame 1.

A rigid diagonal brace 5 leads from the 50 leg 2 to the hub 3. A swinging brace is provided with a long arm 6 and a short arm 7, which brace is pivoted to the frame at 8. The long arm 6 of this swinging brace is provided near its end with a notch 9 ar-

ranged to engage a lock pin 10, projecting 65 from the folding leg 2.

A keeper 11 is mounted on the lock pin 10 in position to guide and hold the long arm 6 of the swinging brace in its position on the leg.

A stop pin 12 is secured to the frame in position to engage the short arm 7 of the swinging brace as the leg nears the limit of its unfolded position, to force the long arm against the lock pin 10 so as to cause it to 65 snap into the notch 9 as the leg reaches the limit of its unfolding movement.

To maintain the leg in its folded position, the long arm 6 of the swinging brace has a tendency to yield inwardly beyond the leg 70 and thereby create a frictional engagement which will tend to keep the leg in its folded position.

To prevent the swinging brace from being pulled through the keeper and to prevent the leg from being swung toward the normal limit of its unfolded position, I provide the brace with a stop device, which device also serves as a handle for the ready manipulation of the brace to release it from 80 the leg when it is desired to fold the leg.

I have shown in the present instance this combined stop and handle as being provided for by twisting the free end of the brace as shown at 13, thus forming a shoulder 14 85 which will prevent the brace from being drawn through the keeper.

It is evident that various changes may be made in this combined stop and handle without departing from the spirit and scope of 90 my invention; hence I do not wish to be limited to the particular embodiment herein shown and described, but

What I claim is:—

1. In a table, a folding leg, and a swinging brace connected at one end thereof to said table, said brace being of flat material slidably connected to the leg, the free end of the brace being twisted to form a shoulder which abuts against the connection between the leg and brace to prevent the leg from being swung beyond the normal limit of its 100 unfolded position.

2. In a table, a folding leg, and a swinging brace connected at one end thereof to 105 said table, said brace being of flat material slidably connected to the leg, the free end of the brace being twisted to form a shoulder

which abuts against the connection between the leg and brace to prevent the leg from being swung beyond the normal limit of its unfolded position, the brace beyond the 6 shoulder being developed into a handle to permit the ready manipulation of the brace for releasing it from the leg when it is desired to fold the leg.

3. In a table, a folding leg, a keeper there-
10 on, a lock pin connected with said leg, and a swinging brace of flat material secured at one end thereof to the table and slideable in the keeper and having a notch for coaction with the lock pin to hold the leg in its un-
15 folded position, the free end of said brace being twisted to form a shoulder which abuts against the keeper to prevent the leg from being swung beyond the normal limit of its unfolded position.

4. In a table, a folding leg, a keeper there- 20 on, a lock pin connected with said leg and a swinging brace of flat material connected at one end with said table and slideable in the keeper, said brace having a notch for coaction with the lock pin to hold the leg in its 25 unfolded position, the free end of said brace being twisted to form a shoulder which abuts against the keeper to prevent the leg from being swung beyond the normal limit of its unfolded position, the brace beyond the 30 shoulder being developed into a handle to permit the ready manipulation of the brace for releasing it from the lock pin when it is desired to fold the leg.

In testimony, that I claim the foregoing 35 as my invention, I have signed my name this 12th day of August 1921.

LOUIS FERGUSON.
